UNITED STATES PATENT OFFICE.

FREDERICK E. KOHLER, OF CANTON, OHIO.

DESIGN FOR A STABLE-COMB.

SPECIFICATION forming part of Design No. 22,537, dated June 13, 1893.

Application filed April 13, 1893. Serial No. 470,252. Term of patent 7 years.

To all whom it may concern:

Be it known that I, FREDERICK E. KOHLER, a citizen of the United States, and a resident of Canton, county of Stark, State of Ohio, have invented and produced a new and original Design for a Mane Comb and Scraper, of which the following is a full, clear, and exact description, reference being had to the accompanying drawing, making part of this specification.

My design relates to a stable comb, and its leading feature consists in forming a plate with teeth and a scraper, on a curved or wave line and also forming it with a series of oblong holes, at each side of the handle, with curved or rounded ends, as will hereinafter more fully appear.

The accompanying drawing represents a perspective view of the combined stable comb showing my design.

In the drawing the reference numeral 1 designates the handle secured to the plate 2 formed with a series of teeth 3. The plate is curved in a longitudinal direction as shown at 4. The numeral 5, designates four oblong 25 holes in the plate, two at each side of the handle having their ends curved or rounded as seen at 6. The numeral 7 designates the scraper, secured to the said plate.

A stable comb according to my design is 30 very ornamental and attractive in appearance.

What I claim is—

The design for a stable comb herein shown and described.

In testimony whereof I have hereunto set 35 my hand this 29th day of March, A. D. 1893.

FREDERICK E. KOHLER.
